(57) **CLAIM**

I claim the ornamental design for a rounded-top box, as shown and described.

DESCRIPTION

FIG. 1 is a perspective view of a first rounded-top box showing our new design in an open position.

FIG. 2 is a perspective view of the rounded-top box of FIG. 1 in a closed position.

FIG. 3 is a front view of the rounded-top box of FIG. 1 in the closed position.

FIG. 4 is a first side view of the rounded-top box of FIG. 1 in the closed position, the second side view being a mirror image of the first side view.

FIG. 5 is a top view of the rounded-top box of FIG. 1 in the closed position.

FIG. 6 is a back view of the rounded-top box of FIG. 1 in the closed position.

FIG. 7 is a perspective view of a second rounded-top box showing our new design in an open position.

FIG. 8 is a perspective view of the rounded-top box of FIG. 7 in a closed position.

FIG. 9 is a front view of the rounded-top box of FIG. 7 in the closed position.

FIG. 10 is a first side view of the rounded-top box of FIG. 7 in the closed position, the second side view being a mirror image of the first side view.

FIG. 11 is a top view of the rounded-top box of FIG. 7 in the closed position; and,

FIG. 12 is a back view of the rounded-top box of FIG. 7 in the closed position.

The broken line depictions of the shoes and other structure are included for environmental purposes and form no part of the claimed design.
